UNITED STATES PATENT OFFICE.

HENRY E. LE GENDRE, OF CRESKILL, NEW JERSEY.

PNEUMATIC TOOL.

1,083,369.

Specification of Letters Patent.

Patented Jan. 6, 1914.

Application filed June 12, 1913. Serial No. 773,220.

To all whom it may concern:

Be it known that I, HENRY E. LE GENDRE, a citizen of the United States, and a resident of Creskill, in the county of Bergen and State of New Jersey, have invented certain new and useful Improvements in Pneumatic Tools, of which the following is a specification.

The present invention relates to pneumatic tools and has for one of its objects means whereby the same tool may be used to obtain both power strokes and finishing strokes, that is, strokes of varying intensity.

Another object of the invention is to produce a smooth-working efficient tool.

Accordingly one feature of the invention resides in providing means whereby the stroke in the cylinder of the piston may be varied to produce blows of a different character, without varying the amount of motive fluid admitted to the tool. The specific means for carrying this into effect reside in a reversible member fitted within the cylinder and which in one position will permit the piston to travel a certain distance, and in another position will permit the piston to travel only a limited distance. In other words, the reversible member by its position varies the effective length of the cylinder.

The invention further consists in a new method and means for actuating the piston, which consists in alternately admitting motive fluid to and exhausting said fluid from one side of the piston, and in continuously admitting a limited amount of motive fluid to and intermittently exhausting said fluid from the other side of the piston.

In the accompanying drawings the invention is embodied in a concrete and preferred form, but changes in the disclosure shown may be made within the scope of the claims, without departing from the legitimate and intended scope of the invention.

In the said drawings: Figures 1 and 2 are vertical longitudinal sectional views taken at right angles to each other through the tool. Fig. 3 is a transverse sectional view on the line 3—3 of Fig. 1. Fig. 4 is a similar view on the line 4—4 of Fig. 2. Fig. 5 is a vertical longitudinal section, partly in elevation, of the upper end of a modified form of the tool.

Similar characters of reference indicate corresponding parts in the several views.

1 indicates a casing or cylinder of any

suitable construction and 2 is a plunger or piston working within this casing. The form of tool shown in the drawings is of a well-known construction and constitutes merely one embodiment of the invention. Motive fluid is led through the inlet 3 to the cross passages 4, down the longitudinal passages 5 to the openings 6, with which register at the proper moment the reduced portion 7 of the piston, permitting the air to flow from the passages in the cylinder up through the passages 8 in the piston to the rear of the said piston, thereby causing it to move in one direction. At the proper moment of the downward movement of the piston, the passages 6 are closed and the exhaust openings 9 are opened. These exhaust openings lead to the passages 10 in the casing communicating with exhaust opening 11. The passage 5 in the casing is carried down into the lower end of the casing, where it terminates in a limited air inlet 12 which feeds motive fluid constantly into the lower portion of the casing. As the piston descends, the motive fluid will be constantly entering in limited quantities through the inlet 12, and will gradually form an air cushion, which of course becomes more pronounced as the piston descends. When the piston has descended far enough to uncover the exhaust openings 9, the air cushion formed below the piston will become effective to move the said piston in the opposite direction, and this motion will then continue until the said piston uncovers the exhaust openings 13 communicating with the passage 10, whereby the air cushion produced by the air entering through the inlet 12 will be exhausted and the piston will commence its forward stroke again.

The casing is provided with a shoulder or supporting ledge 14 near its upper end, on which shoulder rests a cup-shaped member 15 of an inside diameter equal to the general inside diameter of the casing, so that the piston in its upward travel may enter within said cup-shaped member. This is illustrated particularly in Fig. 1 where it will be noted that the member 15 is placed in a position where it forms a continuation of the casing and therefore permits the full stroke of the piston. By this means heavy powerful strokes can be obtained, particularly effective in stone cutting tools when doing the rough preliminary cutting. In Fig. 2 the member 15 is shown in inverted or

reversed position, the bottom 16 forming a closure which decreases the effective length of the cylinder and forms a surface against which the piston strikes, thereby limiting its movement and producing gentler strokes, which are particularly useful for the final finishing work.

It will be apprehended that the strokes of two different sizes of tools may thus be obtained by means of a single tool, and this without varying the air pressure. It will also be noted that the member 15 is located below the transverse openings and that when in either position the full air pressure from

15 the inlet 3 bears upon the said member 15.

It will be apparent that when it is desired to have the long stroke of the piston, the member 15 may be removed altogether from the tool, but it is an additional advantage to be able to have this member in the tool, since it prevents this member being lost or misplaced.

In Fig. 5 is shown a modified form of the invention, in which the member 15 is formed 25 as a smooth-faced extension on the threaded member 3^a. When so constructed it of course becomes necessary when desiring a long stroke to substitute another threaded member, 3^b, as shown in Fig. 1, the member 30 3^b being devoid of this smooth extension. When the modification shown in Fig. 5 is

used the passages 4 will be formed directly in the member 3^a and will come opposite the passages 5 so that the incoming air may have communication with the said passages 5.

What is claimed, is:

1. In a valveless pneumatic tool, a cylinder, a piston, means for reciprocating the piston, and means for varying the stroke of the piston by varying the effective length of the cylinder.

2. In a pneumatic tool, a cylinder, a piston, means for reciprocating the piston within the cylinder, and a reversible member supported within the cylinder for varying the effective length of the cylinder.

3. In a valveless pneumatic tool, a cylinder having intake and exhaust ports, a piston, means for reciprocating said piston within the cylinder, and means for varying the effective length of the cylinder without correspondingly changing the position of either intake or exhaust ports.

Signed at Plymouth and Adams streets, 55
borough of Brooklyn and city of New York,
in the county of Kings and State of New
York, this 9th day of June, A. D. 1913.

HENRY E. LE GENDRE.
